United States Patent Office

Des. 193,781
Patented Oct. 9, 1962

193,781

AUDIOMETER

Paul A. Hoogesteger, Brighton, N.Y., and Jacob W. Patla, Penn Township, Westmoreland County, Pa., assignors to Bausch & Lomb Incorporated, Rochester, N.Y., a corporation of New York

Filed Feb. 5, 1962, Ser. No. 68,665

Term of patent 14 years

(Cl. D26—1)

FIG. 1

FIG. 2

FIG. 3

FIG. 4

FIG. 1 is a front perspective view of an audiometer showing our new design;

FIG. 2 is a front perspective view of an audiometer showing our new design in operating position;

FIG. 3 is a back perspective view thereof; and

FIG. 4 is a side view thereof which both sides are the same.

We claim:

The ornamental design of an audiometer, substantially as shown and described.
